CLIP FOR TRAIN ORDER HOLDERS

Myren A. Williams, Greenville, Pa.

Application April 5, 1940, Serial No. 328,116

1 Claim. (Cl. 24—129)

This invention relates to a clip for use upon train order holders, and has for one of its objects the production of a simple and efficient means for detachably holding a train order or similar message to be delivered to a moving vehicle, such as a train and the like.

A further object of this invention is the production of a simple and efficient spring clip for detachably holding the message-carrying line or cord in engagement with a holder.

Other objects and advantages of the present invention will appear throughout the following specification and claim.

In the drawing:

Figure 1 is a side elevational view of the train order holder;

Figure 2 is an edge elevational view of the train order holder;

Figure 3 is a sectional perspective view taken on line 3—3 of Figure 1;

Figure 4 is a perspective view of one of the cord-engaging spring clips.

By referring to the drawing, it will be seen that 10 designates the staff of the train order holder. The staff 10 carries arms 11 and 12 and each of these arms carries a shank 14 for snugly engaging the upper end of the staff 10. A bolt 15 secures the shank 14 in engagement with the staff 10. Each arm 11 and 12 is provided with a channel portion 16 extending for a major portion of its length and a flattened or flared portion 17 is provided in each arm 11 and 12 intermediate the shank 14 and the channel portion 16.

The message-carrying cord 18 fits in the channel portion 16 and spans the outer ends of the arms 11 and 12, as shown in Figure 1. The message 19 is carried by that portion of the cord 18 which extends between the outer ends of the arms 11 and 12. The flattened or flared portions 17 provide relatively shallow channels which will permit the lower end of the message-carrying cord 18 to conveniently engage one of the spring clips 20. Two of these spring clips 20 are provided, one upon each side of the handle 10, as shown in Figure 1.

Each spring clip 20 comprises an elongated shank portion 21 which normally lies flat against the side of the handle 10, as shown in Figure 2. The shank portion 21 carries at its outer end an outwardly turned lip 22 which extends slightly above the upper end 23 of the handle 10. The lower end of the shank 21 is provided with an outwardly bulged portion 24 to provide a cord-

receiving pocket 25. This outwardly bulged portion terminates in an outwardly inclined end 26 which outwardly inclined end 26 carries an inturned gripping or biting jaw 27 the periphery of which is concave, as at 28, to provide laterally spaced biting corner spurs 28^a, the corner spurs 28^a and concave periphery being adapted to dig into the outer face of the handle 10 and hold the clip 20 against lateral swinging movement and 5 in proper longitudinal relation with respect to the handle 10. An anchoring bolt 29 is extended through the outwardly inclined end 26 of the opposite clips 20, as shown in Figure 2, and this bolt also extends through the handle 10 for 10 anchoring the clips 20 upon the handle. The biting jaw 27 will bite into the sides of the handle 10 and when the anchoring bolt 29 is in position, the biting jaws 27 of the clips 20 will be 15 drawn into biting engagement with the handle 10 thereby firmly holding the clips in proper 20 longitudinal relation with respect to the handle and anchoring the clips against swinging movement. The clips 20 are preferably of spring metal and the elongated shank 21 of each clip 25 will tend to hold the cord 18 within the socket 24 in view of the fact that the shank portion 21 of each clip will normally lie flat against the sides of the handle 10. In view of the fact that 30 the lips 22 extend slightly above the upper end 23 of the handle 10, the cord may be easily slipped between the upper end of the handle 10 and the lip 22 by placing the cord upon the upper end of the handle 10 and drawing the cord downwardly against the outwardly turned 35 lip 22 it will direct the cord to a position between the handle 10 and the shank 21, at the same time forcing the shank 21 outwardly until the cord reaches the pocket 25.

40 By considering Figure 1, it will be seen that the cord 18 will be firmly held within the channel 16 and when the cord is drawn to the position of engagement with the pocket 25 of one of the clips 20, the flattened or flared portions 17 of the arms 11 and 12 will permit the cord 18 to be moved laterally for this engagement, as shown 45 in Figure 2, and at the same time will facilitate the removal of the cord 18 from the arms 11 and 12 and the engaging clip 20 while the message 19 is being delivered in the conventional manner. 50 Certain detail changes in the mechanical construction may be employed without departing from the spirit of the invention so long as such changes fall within the scope of the appended claim.

Having described the invention, what I claim as new is:

As an article of manufacture, a clip for use upon train order holders, the clip comprising a body having an elongated shank adapted to normally lie flat against a supporting handle, the shank carrying a cord-receiving pocket near one end, an outwardly inclined bolt-receiving portion adjacent the pocket, said clip having an inturned biting jaw at the end of said outwardly inclined portion, the jaw having a concave pe-

riphery defining laterally spaced corner spurs, the corner spurs and concave periphery of the biting jaw being adapted to dig into the outer face of a handle to hold the clip against lateral swing and in proper longitudinal relation with respect to a handle, and a single anchoring bolt passing through said outwardly inclined portion for clamping the biting jaw into engagement with a handle and holding the clip normally flat against the supporting handle.

MYRON A. WILLIAMS.
